FEEDING MECHANISM FOR WIRE STITCHING MACHINES.
APPLICATION FILED OCT. 18, 1911.

Patented Nov. 11, 1913.

2 SHEETS-SHEET 2.

FIG. 2.

UNITED STATES PATENT OFFICE.

HENRY WEBER, OF CHICAGO, ILLINOIS, ASSIGNOR TO LATHAM MACHINERY COMPANY, OF CHICAGO, ILLINOIS, A CORPORATION OF ILLINOIS.

FEEDING MECHANISM FOR WIRE-STITCHING MACHINES.

1,078,024.

Specification of Letters Patent. Patented Nov. 11, 1913.

Application filed October 18, 1911. Serial No. 655,849.

To all whom it may concern:

Be it known that I, HENRY WEBER, a citizen of the United States, residing at Chicago, in the county of Cook and State of Illinois, have invented certain new and useful Improvements in Feeding Mechanism for Wire-Stitching Machines, of which the following is a specification.

This invention relates in general to wire stitching or stapling machines, and more particularly to the mechanism for feeding and cutting the wire preparatory to the forming of the staple, and has for one of its objects to provide an improved machine of this class having means for simultaneously adjusting the feeding mechanism with the cutter for regulating the length of the legs of the staple.

A further object is to provide an improved apparatus of this class which will be simple, durable and cheap in construction and effective and efficient in operation.

To the attainment of these ends and the accomplishment of other new and useful objects, as will appear, the invention consists in the features of novelty in substantially the construction, combination and arrangement of the several parts hereinafter more fully described and claimed and shown in the accompanying drawings, illustrating an example of the invention, and in which—

Figure 1 is a face view of the head of a wire stitching machine embodying this invention; Fig. 2 is a sectional view on line 2—2, Fig. 1; Fig. 3 is a sectional view on line 3—3, Fig. 1; Fig. 4 is a sectional view on line 4—4, Fig. 1; Fig. 5 is a detail sectional view of the wire gripping or feeding dog; Fig. 6 is a perspective view of the pivot pin of the dog.

As is usual in machines of this character, the wire from which the staples are formed is supplied from the ordinary reel and passes through a suitable wire guide 8 for holding it firmly while it is engaged by a cutter-blade 11. In the present exemplification of the invention, the wire guide is shown as a tube 8 which is arranged in the cutter-block 9, suitably supported on a frame 10, and having one face 12 flush with the extremity of the guide tube 8. The cutter 11 rests and slides against this face 12 and is provided with means for securing the same to a shank 13, such as a screw 14, which

passes through the cutter 11 and has engagement with the shank 13. The shank 13 slides within the cutter-block 9 and is preferably cylindrical. The upper end of the shank is connected to means for receiving motion from the usual cam shaft 15, or some other moving part of the machine for causing the cutter blade 11 to move across the end of the wire tube 8, and thereby sever the wire projecting therethrough. For this purpose, the end of the shank is formed with two flanges 16—17, which, for convenience in manufacture, may be cylindrical and turned up thereon or formed in any suitable way, and between which flanges engages a bar or arm 18 secured to the end of the rod 19, in any suitable manner. The upper end of the rod 19 is arranged to be engaged at the proper time by a cam 20 secured to the cam shaft 15 or any other suitable moving part of the machine whereby the rod 19 will be depressed and the wire severed during each revolution of the cam shaft. To reduce friction, the end of the rod 19 is provided with an anti-friction roller 21 for the engagement of the cam 20, and to facilitate and reduce the cost of manufacture, the rod is made cylindrical so that its socket in which it is held and guided may be formed by a drill. This socket is formed in a frame 22, or any other suitable support provided adjacent the rod 19, having a socket 23 therein parallel with the rod 19, and so close thereto as to constitute a continuation of the socket of the rod 19, whereby a pin 24, which is secured to the rod 19 may project into the socket 23, and engage with one end of the spring 25 located in the socket 23 for returning the rod 19 to its elevated position when released by the cam 20. This pin 24, by projecting from one socket to the other, also constitutes means for holding the rod 19 against rotation.

When it is desired to remove the cutter-blade for sharpening or for the substitution of a new blade, it is only necessary to remove the screw 26 which holds the cutter-block 9 in place in the frame 10, thereby allowing the block to be withdrawn in an upward direction away from the arm 18.

The cutter block 9 together with the blade 11 may be adjusted back and forth with relation to the staple forming and driving mechanism ordinarily housed within the

head 27, notwithstanding the connection of the shank 13 with the rod 19, because, as is readily seen, the flanges 16-17 slide along such arm during this adjustment without destroying the connection between the shank 13 and the rod 19. This adjustment of the cutter-block and cutter-blade may be effected in the usual or any suitable way. In the exemplification of the invention shown in the drawings, the frame 10 is attached to a slide 28 mounted for movement, in a slot 29 in the main frame member 30, and this slide is engaged by a threaded portion 31 of a rod 32 journaled in a support 33 on the frame member 30 and held against the longitudinal movement with such journal 33. The rod is also provided with a handle 34 by means of which it may be rotated, and by the rotation of this knob or handle 34, the frame 10 will be adjusted with relation to the head 27 which houses the staple forming and driving devices.

In order to advance the wire from which the staple is formed, to the stapling or stitching mechanism as well as to the cutter blade 11, there is provided a feeding dog designated generally by the reference numeral 35 which is mounted upon a slide 36, and this slide 36 is mounted to reciprocate upon guides 37 on the frame 10. The dog 35 is provided with a serrated face 38 which coöperates with a support 39 for the wire, to grip the wire, and as the slide 36 is moved by the oscillating arm 40, to which it is secured by a pin and slot connection pivoted to fixed support 41, toward the head 27, the wire will be gripped and forced through the guide 10. This arm 40 is provided with an extension 42 at the end of which is journaled an anti-friction roller 43, whereby the arm 40 is rocked by a cam 44 connected to the cam shaft 15. As the shaft 15 rotates, the cam 44 will engage the extremity of the arm 42 and rock the arm 40 in a direction to move the slide 36 toward the head. This arm 40 is usually returned by means of an elastic member coiled about the pivot 41. When the arm is returned after having been moved by the cam 44, the slide 36 will also be returned to secure a new grip on the wire.

In order to hold the wire against retrograde movement when the slide 36 is being returned, a retaining dog 45 is provided which coöperates with a support 46 to grip the wire. This dog 45 is preferably in the form of a disk having ratchet teeth 47 with which a spring pawl 48 coöperates so as to permit the dog 45 to rotate in one direction 60 and to lock it against rotation in the opposite direction.

In order to release the wire from the feeding dog when the latter reaches the limit of its feeding movement, there is provided 65 a stop 49 having a threaded extremity 50

which engages in a projecting portion or arm 51 on a slide 52. This slide 52 is preferably arranged on the side of the main frame 30 opposite the side on which the frame 10 is arranged and the arm or projecting portion 51 extending through the slot 29 in the frame 30 and also through a slot 53 in the frame 10, and is of sufficient length, to project some distance beyond the front of the frame 10 so that the end of the stop 49 which is mounted in this arm or extension 51, will be disposed within the path of movement of an extension 54 on the dog 35. When the slide 36 is moved in a direction to feed the wire, the extension 54 on the dog 35 will engage the extremity of the stop 49 and the latter will rock the dog to release the wire. This stop 49 is adjustably secured to its support so that it may be adjusted to take up the wear on the extremity at the end of the stop, and a fastening device 55 is provided for securing the stop against accidental displacement with respect to the support 51.

In order to vary the time of the engagement of the extremity 54 of the dog 35 with the stop 50 to release the wire, and thereby regulate the amount of wire which is fed to the staple forming mechanism, the stop 49 is mounted upon the slide 52, and this slide has connection with the rod 32 by means of a threaded portion 56 engaging the slide 52. This threaded portion 56 is opposed to the threaded portion 31, that is, the threads run in opposite direction so that when the rod 32 is rotated by the knob or handle 34, the slides or supports 10-52 will be adjusted toward or away from each other according to the direction of rotation of the rod 32 as will be understood, and this adjustment will move the cutter-block 9 together with the cutter-blade 11 toward or away from the head 27, while at the same time the stop 49 will be adjusted with respect to the cutter-block 9 to position the stop 49 to be engaged by the extension 54 on the dog 35 at different points in the line of travel or feeding movement of the dog 35. This adjustment is provided for the purpose of regulating or varying the length of the legs of the staple. If the slide 36 is allowed to travel the full length of the movement of the arm 40, before it is tripped to release the wire, the staple legs will be of considerable length, but if the stop 49 is adjusted to trip the dog 35 before the slide reaches the limit of its travel or feeding movement, a less amount of wire will be fed to the stapling mechanism and cutter and therefore the staple legs will be shorter.

The feeding dog 35 is pivotally mounted upon the slide 36 by means of a pivot pin 57 which preferably has a cylindrical body 58 having a flattened or shouldered portion 59. The pivot pin passes through an aper-

ture 60 in the dog 35 and has a threaded extremity 61 which engages the slide 36. When thus secured to the slide 36 the dog 35 is mounted for free pivotal movement about the pivot pin 57. The dog is provided with a passage 62 which extends obliquely from the aperture 60 to the bearing face of the dog and a contact member 63 is mounted in the upper end of the passage 62 to project into the aperture 60 so as to engage the periphery of a pivot pin 57, and an elastic member 64 is mounted in the passage 62 which tends normally to force the member 63 into engagement with the pivot pin. A removable plug 65 is threaded into the lower end of the passage 62 and forms an abutment for one end of the same and also a means whereby the tension of the elastic member 64 may be varied.

20. When the dog 35 is in a gripping position or in the position shown in Fig. 5, the member 63 will be in engagement with the shoulder or flattened portion 59 of the pivot pin, and when in engagement with this portion, the normal tendency of the elastic member 64 is to force the dog 35 in a direction to grip the wire and will hold it in this position as long as the member 63 engages the flattened or shouldered portion 59. The dog 30 will thus grip the wire during the movement of the slide 36 and will hold the wire until the extremity 54 of the dog engages the extremity of the stop 49, which latter will rock the dog about its pivot pin 58 and will 35 move the member 63 out of contact with the flattened or shouldered portion 59 of the pivot pin into a position so that it will engage the rounded portion of the periphery. This movement of the dog will overcome the 40 tension or tendency of the elastic member 64 to force the dog into a gripping position, and will retain the dog in its inoperative position until the dog is moved by some other means than the elastic member to force the 45 member 63 again into engagement with the flattened or shouldered portion 59. This last movement of the dog may be accomplished by means of another stop 67 which is adjustably mounted in any fixed portion of the 50 mechanism and extends within the path of the returning movement of the extension 54 of the dog 35 to be engaged by such extension before the slide 36 reaches the limit of its return movement. This will force the dog 35 55 back to its normal position so that the member 63 will engage the flattened or shoulder portion 59 of the pivot pin. It will thus be manifest that the operation of the dog 35 to release the wire is controlled by the position of the stop 49 which latter is positioned by the operation of the rod 32, and inasmuch as this rod also has connection with the cutter-block 9 for adjusting the same with respect to the staple forming mechanism, the 60 operation of this rod will simultaneously ad-

just the stop 49 and the cutter-block 9 with respect to each other, and also the cutter-block 9 with respect to the staple forming or stitching mechanism.

From the foregoing description it will be seen that the operation of the mechanism described will be as follows: Assuming the elements to be in the position shown in Fig. 1 and the shaft 15 to be rotating, the cam 44 will engage the friction roller 43 of the arm 41 and will oscillate the same about its pivotal point. This movement of the arm 41 will cause the slide 36 carrying the dog 35 to move toward the head 27 in which is mounted the staple forming and stitching mechanism. This movement of the slide will be prior to any movement of the rod 19 and the shank 13 carrying the cutter blade 11 and also the staple forming and stitching mechanism, and consequently the wire engaged by the dog 35 will be fed and located under the staple forming and stitching mechanism prior to being severed, formed or driven. During this movement of the slide 36 the spring 64 within the dog will force the member 63 into engagement with the flattened portion 59 of the pivot pin 57, and thus retain the bearing face of the dog in such a position that the serrations 38 thereof will engage the wire and clamp the same between said bearing face and the seat 39. When the slide 36 has fed sufficient wire through the cutter-block 9, depending on the adjustment of the stop 49, the projection 54 of the dog will contact with said stop 49 and swing said dog about the pivot pin 57, thus causing the friction member 63 to bear against the rounded surface of the pivot pin 57 during the retrograde movement of the slide, thereby retaining the dog 35 in an elevated position above the seat 39 to prevent the serrated face 38 thereof from contacting with the wire. At the end of the retrograde movement of the slide the projection 54 will engage the stop 67 swinging the dog 35 about the pivot pin to the position illustrated in Figs. 1 and 5 where the serrated face 38 of the dog will clamp the wire against the seat 39. By rotating the handle 34, the shaft or rod 32 will rotate and through the instrumentality of the oppositely disposed threads 31 and 56 will adjust the slides 28 and 52 to and from one another. This movement of the slides 28 and 52 will simultaneously adjust the cutter-block 9 and the cutter-blade 11 with respect to the head 27 to sever more or less wire as the case may be, dependent on the direction of adjustment, and the stop 49 to release the wire at the proper point in the operation just prior to the movement of the 125 cutter-blade 11.

What is claimed as new is:

1. In a machine for the purpose described, the combination of a wire feed dog for gripping and feeding the wire, a pivot

element about which the dog is movable, yielding means carried by the dog and frictionally engaging the pivot element and tending normally to move the dog into operating position to grip the wire, said means also operating on the pivot to hold the dog in an inoperative position, means for moving the dog into an inoperative position, and means for moving the dog into an operating position.

2. In a machine for the purpose described, the combination of a wire feed dog for gripping and feeding the wire, a pivot element about which the dog is movable, yielding

means carried by the dog and frictionally engaging the pivot element and tending normally to move the dog into operating position to grip the wire, said means also operating on the pivot to hold the dog in an inoperative position, spaced stops between which the dog is movable to respectively move the latter into and out of operating position, and means for moving the dog into and out of engagement with the stops.

3. A gripping dog for wire stitching machines or the like embodying a wire support, a dog coöperating therewith, a pivot element for the dog and about which the dog is movable, said element having a shouldered portion, and elastic means carried by the dog and coöperating with the said shouldered portion to normally move the dog to grip the wire, said elastic means also coöperating with another portion of the pivot element to hold the dog in an inoperative position.

4. A gripping dog for wire stitching machines or the like embodying a wire support, a dog coöperating therewith, a pivot element for the dog and about which the dog is movable, said element having a shouldered portion, and elastic means carried by the dog and coöperating with the said shouldered portion to normally move the dog to grip the wire, said elastic means also coöperating with another portion of the pivot element to yieldingly hold the dog in an inoperative position.

5. The combination with a wire feeding and gripping dog mounted for reciprocation, of a pivot therefor, a yielding friction element arranged to operate against said pivot and normally force said dog into a gripping position, said yielding friction element likewise adapted to retain said dog in a non-gripping position, and means located at the terminals of the path of movement of said dog for placing the said dog in a gripping or non-gripping position as the case may be.

6. The combination with a wire gripping and feeding dog mounted for reciprocation, of a pivot therefor, a yieldable friction element mounted within the dog arranged to engage the pivot aforesaid for normally moving the dog into a gripping position and

also at predetermined intervals retaining the dog in a non-gripping position, and stops arranged at the terminals of the path of movement of said dog for placing the same in a gripping or non-gripping position as the case may be.

7. The combination with a wire gripping and feeding dog mounted for reciprocation, of a pivot therefor, a yieldable friction element mounted within the dog arranged to engage the pivot aforesaid for normally moving the dog into a gripping position and also at predetermined intervals retaining the dog in a non-gripping position, and adjustable stops arranged at the terminals of the path of movement of said dog for placing the same in a gripping or non-gripping position as the case may be.

8. The combination with a feeding dog adapted to alternately grip and release a wire, of independent operating means for said dog whereby said gripping and said releasing action is created, and means whereby said independent operating means may be relatively adjusted.

9. The combination with a reciprocatory feeding dog for alternately gripping and releasing a wire, of stops at the terminals of the path of movement of said dog for causing said releasing and gripping action, and means for varying the distance between said stops thereby adjusting the point of grip and point of release of the wire.

10. The combination with a feeding dog adapted to alternately grip and release a wire, of independent means for controlling the automatic gripping and releasing of said wire, and means whereby the releasing point and gripping point may be relatively and simultaneously adjusted.

11. The combination with a feeding dog, of an adjustable gripping stop, an adjustable releasing stop, and means for relatively adjusting said stops with respect to each other.

12. The combination with a feeding dog adapted to alternately grip and release a wire, of a stop adapted to cause the release of said wire, said stop being adjustable, a releasing stop coöperating with said dog, and means for simultaneously adjusting said stops to or from one another.

13. The combination with an alternately gripping and releasing dog, of a cutter-block, a stop independent of said block for controlling the point of release, and means for simultaneously adjusting said cutter-block and said stop.

14. The combination with a dog, of a cutter-block, a stop coöperating with said dog, and means for simultaneously adjusting said cutter-block and stop to and from one another.

15. The combination with a frame, of a cutter-block carried thereby, a dog mounted

- for reciprocation thereon, a stop coöperating with said dog and said frame, and means for simultaneously adjusting said frame and said stop.
- 5 16. The combination with a frame, of a cutter-block carried thereby, a dog mounted for reciprocation thereon, a slide, a stop carried by said slide, and coöperating with said dog and frame, and means for simultaneously adjusting said slide and said frame.
- 10 17. The combination with a frame, of a cutter-block carried thereby, a primary slide secured to said frame, a secondary slide arranged adjacent thereto, a stop carried by said secondary slide, and means coöperating with said slides for adjusting the same to and from one another.
- 15 18. The combination with a frame, of a cutter-block carried by said frame, a dog mounted for reciprocation of said frame, a slide secured to said frame and adapted to move therewith, a second slide located adjacent to said frame, a stop carried by said second slide adapted to lie in the path of movement of said dog, and means for adjusting said slides to and from one another, thereby changing the relative positions of said stop and cutter-block.
- 20 19. The combination with a frame, of a cutter-block carried by said frame, a dog mounted for reciprocation of said frame, a slide secured to said frame and adapted to move therewith, a second slide located adjacent to said frame, a stop carried by said second slide adapted to lie in the path of movement of said dog, and a shaft piercing said slide and coöperating therewith
- 25 through the instrumentality of oppositely arranged threads.
20. The combination with a support, of a pivot pin carried thereby, a dog mounted for movement upon said pivot pin, and a frictional means carried by said dog adapted to retain the dog in adjusted positions.
- 40 21. The combination with a support, of a pivot pin carried thereby, a dog mounted for movement on said pivot pin, and means carried by said dog for engagement with the pivot pin to retain said dog in adjusted positions.
- 45 22. The combination with a support, having a seat formed thereon, of a pivot pin carried thereby, a dog mounted for movement on said pivot pin for coöperation with said seat, and means carried by said dog for engagement with said pin to retain the former in adjusted positions with respect to said seat.
- 50 23. The combination with a support, of a pivot pin carried thereby having a flattened face, a dog mounted for movement upon said pivot pin, and a spring-pressed plunger for frictional engagement with the flattened and rounded surfaces of said pivot pin for retaining the said dog in adjusted position.
- 55 In testimony whereof I have signed my name to this specification, in the presence of two subscribing witnesses, on this 16th day of October, A. D. 1911.
